UNITED STATES PATENT OFFICE.

THOMAS J. KERWIN, OF CHICAGO, ILLINOIS, ASSIGNOR TO EDMUND & JONES CORPORATION, A CORPORATION OF NEW YORK.

INSTRUMENT-BOARD LAMP.

Application filed October 21, 1920. Serial No. 418,527.

To all whom it may concern:

Be it known that I, THOMAS J. KERWIN, citizen of the United States, residing at Chicago, in the county of Cook and State 5 of Illinois, have invented certain new and useful Improvements in an Instrument-Board Lamp; and I do hereby declare the following to be a full, clear, and exact description of the invention, such as will enable others skilled in the art to which it 10 pertains to make and use the same.

My invention relates to electric fittings suitable for use with the type of incandescent lamps which has a pair of exposed terminals upon the base of the lamp, one of its general aims being that of providing a novel switching socket which can readily be manipulated for turning the lamp on or off, in which the cooperating 15 contact parts will be yieldingly latched either in their "on" or "off" positions, and in which this latching is preferably accomplished by the same spring means which insure good electrical connection between 20 the circuit terminals of the socket and the terminals of the lamp.

In another aspect, my invention aims to provide a lamp socket equipped with a hood or reflector for the lamp and so arranged 25 that the socket can readily be switched on or off by manipulating the hood. In this latter aspect, my invention particularly relates to sockets or receptacles suitable for use on the dash-boards of automobiles, and 30 for that purpose aims to provide a socket equipped with a suitable reflector or cowl for properly directing the light of the lamp, to provide simple means operable by a rotational movement of the reflector or cowl in 35 either direction for switching the socket either on or off, and to provide simple and effective means for permitting such a reflector or cowl to be attached to or detached from the socket without interfering with the 40 aforesaid operative connections.

In one of its highly desirable commercial embodiments, my invention relates to a so-called instrument board lamp and I am therefore describing it in such an embodiment in the following specification and correspondingly illustrating it in the accompanying drawings, leaving further and more detailed objects of my invention to appear from the said specification and drawings. In the drawings,

Fig. 1 is an elevation of an instrument board lamp embodying my invention, showing the same as it appears when attached to the dash-board of an automobile.

Fig. 2 is a transverse section through the 60 same, taken along the correspondingly numbered line of Fig. 1.

Fig. 3 is an enlarged central and longitudinal section through the socket and the adjacent portion of the dash-board, taken 65 along the correspondingly numbered line in Fig. 2.

Fig. 4 is a transverse section taken along the correspondingly numbered line in Fig. 3 and showing the relative disposition of 70 the socket terminals and of the lamp terminals both in their "on" and "off" positions.

Fig. 5 is an elevation of the socket and of a portion of the lamp base interlocked 75 therewith, taken from the bottom of Fig. 3 and with the cowl and the cowl carrying cowl omitted.

In the drawing, the lamp 1 has its base 2 equipped with a pair of laterally projecting pins 3 interlocking with bayonet slots 4 in a substantially cylindrical socket shell 5 which slidably receives the said lamp base at its forward end. This socket shell 5 is soldered into a rearwardly directed collar 6 80 on a flange 7 adapted to be fastened to the dash-board 8 of an automobile by screws 9, so that both the socket shell 5 and the lamp are normally stationary. Rearward of the lamp base, the shell 5 houses the usual 85 body portion or circuit-terminal-carrier of a socket of the type commonly used for automobile lamps, namely a rubber cylinder carrying a pair of spring pressed plungers 11 which respectively form terminals for the 90 wires 12 of the circuit, and which plungers contact with exposed terminals 13 on the base of the lamp when the parts are in the position illustrated in Fig. 3. The circuit-terminal-carrier thus described is rotatable 95 within the shell 5, so that it may be turned from the "on" position in which the circuit terminals 11 contact with the lamp terminals 13 as shown in Figs. 3 and 4, to a second position indicated in dotted lines 100 in Fig. 4, in which latter position the two sets of terminals are out of engagement and the lamp is therefore switched off. To provide for a rotation of the circuit terminal-carrier between these two different positions, 105

110

I equip the shell 5 on one side with a slot 14 extending circumferentially of the shell, and I fasten to the insulator 10 a screw 15 which extends outwardly through the 5 lateral slot 14. Consequently, by moving the screw 15 from outside the shell, the circuit-terminal-carrier can be moved from its "on" to its "off" position, or vice versa, so as to switch the lamp on or off. I also desirably make the slot 14 substantially arcuate and convexed towards the forward end of the shell 5, so that a movement of the screw 15 towards the middle of the slot will slide the insulator 10 forwardly of the

15 socket, or towards the base of the lamp. Since such a sliding movement will cause an additional compression of the springs 16 associated with the terminal plungers 11, these springs will resist such a movement 20 of the screw in the slot and will therefore cooperate with the arcuate shape of the slot in normally holding the screw at either one or the other end of the slot.

To move the screw for such switching purposes, I desirably extend the same also 25 through a collar which is rotatable on the shell 5 of the socket, so that the switching may be effected by manually rotating this 30 collar. For this purpose, I am here showing, a collar 17 surrounding the said slotted portion of the shell 5 and having an enlarged forward portion 18 adapted to receive the rear end of a reflecting hood or cowl 19. This collar has an enlargement or 35 bead 20 which might be grasped by hand for rotating the collar and thereby moving the screw 15 to effect the desired switching. However, I preferably interlock the hood 19 with the collar portion 18 by some suitable 40 means, such as the interengaging tits 21, so that the rotation of the circuit-terminal-carrier can be effected by grasping this hood and rotating it for a quarter turn in one direction or the other. To provide a better 45 bearing on the shell 5 for this collar while permitting the same to provide the enlarged forward end desired for holding a cowl, I may interpose a sleeve 22 secured to the said collar 17.

50 With the socket constructed as above described, it will be obvious that the lamp can be switched on or off by merely grasping the hood or cowl 19 (or any other element interlocked with the screw 15 against relative 55 rotation about the axis of the socket) and rotating the same a quarter turn in either direction. Moreover, the mechanism of the socket is firmly latched with the movable pair of contact elements either in its "on" 60 or in its "off" position, so that the accomplished switching is not affected by any jarring. Furthermore, this latching is accomplished by exceedingly simple means and without employing any springs in addition 65 to those associated with the contact plungers

of the socket, thereby insuring a simple and cheap construction and one which has no auxiliary parts likely to get out of order.

However, I do not wish to be limited to this or other details of the construction and 70 arrangement here disclosed, nor to the particular form of hood or reflector here illustrated except so far as defined by the claims, nor to the use of my invention in connection with dash-board lamps. Obviously, various 75 additions, omissions or other alterations might be made without departing from the spirit of my invention as announced by the claims.

I claim as my invention:

1. In a lamp, a stationary member equipped for interlocking with the base of a lamp, an insulator within the member carrying circuit terminals respectively disposed for engaging the terminals of the lamp, the insulator being rotatable within the member to move the said circuit terminals out of engagement with the lamp terminals, a collar housing a portion of the member and fastened to the insulator, and a 90 hood carried by the collar and interlocked therewith, so that a movement of the reflector will rotate the said collar and insulator with respect to the member to switch the lamp on or off. 95

2. In a lamp, a substantially cylindrical shell having a lateral slot, a supporting collar secured to the shell, a rotatable circuit terminal carrier in the shell, a collar rotatably mounted at one end on the shell, 100 and having an outwardly extending peripheral bead between its ends and having its opposite end spaced from the periphery of the shell, a hood disposed about said opposite end of the rotatable collar and abutting the 105 bead at one end, a lamp in the shell, and a member extending through the first named end of the rotatable collar and through the slot of the shell and into the terminal carrier so as to rotate the latter by and upon 110 rotation of the hood and rotatable collar.

3. In a lamp, a supporting member, a lamp with base terminals fixedly carried thereby, a rotatable circuit terminal carrier carried by the supporting member and having wires connected to its terminals and the latter directly engaged with the lamp terminals, a hood for the lamp, means to rotatably connect the hood to said supporting member, and a screw connecting the hood 120 and the circuit carrier whereby rotation of the hood will effect rotation of the carrier to thereby switch the lamp on and off. 115

4. In a lamp, a supporting member, a lamp fixedly carried thereby, a rotatable circuit terminal carrier carried by the supporting member and having wires connected to its terminals and the latter directly engaged with the lamp terminals, a hood for the lamp, a member rotatable on the 130

supporting member, a hood fixed to the rotatable member, and means connecting the rotatable member to the terminal carrier whereby rotation of the hood will effect rotation of the carrier to thereby switch the lamp on and off.

5. In a lamp, a shell, a lamp in the shell having a pair of exposed terminals upon its base, means to rigidly connect the lamp to the shell, a rotatable circuit terminal carrier in the shell having wires connected to its terminals and the latter disposed for direct engagement with those of the lamp, a hood for the lamp rotatably mounted on the shell, and connecting means between the hood and the carrier whereby upon rotation of the hood the carrier will be rotated to cause its terminals to be engaged with or disengaged from the lamp terminals while the latter remains stationary.

6. In a lamp, a shell, a lamp in the shell, means to rigidly connect the lamp to the shell, a rotatable circuit terminal carrier in the shell, a hood for the lamp, means to rotatably mount the hood on the shell, and means for rigidly connecting the hood to

the terminal carrier so that rotation of the hood will rotate the carrier and for preventing longitudinal movement of the hood relative to the shell.

7. In a lamp, a slotted shell, a lamp in the shell, means to rigidly connect the lamp to the shell, a rotatable circuit terminal carrier in the shell, a hood rotatable on the shell, and a fastener connected to the hood and extending through the slot of the shell and connected to the carrier for causing the latter to rotate within the hood to switch the lamp on or off and for preventing longitudinal movement of the hood on the shell.

8. In a lamp, a shell, a lamp having base terminals therein, a hood for the lamp rotatable on the shell, means preventing longitudinal movement of the hood on the shell, and means including a part having terminals that have wiping engagement with the lamp terminals and operated by turning of the hood to switch the lamp on or off.

Signed at Chicago, Illinois, October 16th, 1920.

THOMAS J. KERWIN.
